UNITED STATES PATENT OFFICE.

GEORGE S. BUCK, OF KALISPELL, MONTANA, ASSIGNOR OF ONE-HALF TO
JOHN G. BUCK, OF KALISPELL, MONTANA.

GATE.

No. 803,547.

Specification of Letters Patent.

Patented Nov. 7, 1905,

Application filed March 2, 1905. Serial No. 248,167.

To all whom it may concern:

Be it known that I, GEORGE S. BUCK, a citizen of the United States of America, residing at Kalispell, in the county of Flathead and State of Montana, have invented certain new and useful Improvements in Gates, of which the following is a specification.

This invention relates to gates, and more particularly to that class known as "sliding" gates.

It is an object of the invention to produce a gate of this character that will be operated automatically from a trackway provided for a vehicle.

15 It is also an object of the invention to provide a gate of the class in which a tilting trackway is provided for opening or shutting the gate, said gate having pivoted thereto a wheel or segment adapted to engage said track.

20 Another object of the invention is to provide means in a gate of this kind whereby the weight on the operating-wheel of the gate may be adjusted.

25 Still further, it is the object of the invention to produce means whereby the gate cannot be operated unless a vehicle approaches the gate, or, in other words, means is produced to prevent the accidental opening of the gate.

The invention has also for an object the 30 provision of means for guiding the gate in its operation or holding it against lateral displacement.

A further object of the invention is to provide means, such as weights, on the operating 35 wheel or segment to facilitate the movement thereof.

Further, it is an object of the invention to produce a device of this character that will be simple in construction, efficient in practice, and economical to manufacture.

With the above and other objects in view the invention consists in the details of construction and in the arrangement and combination of parts to be hereinafter more fully 45 described and claimed.

In describing the invention in detail reference will be had to the accompanying drawings, forming part of this specification, wherein like reference characters denote corresponding parts in the several views, and in which—

Figure 1 is a view in side elevation and partly in section of the invention, the gates being closed. Fig. 2 is a view similar to Fig. 1 with the exception that the gates are open.

Fig. 3 is a top plan view of the invention. 55 Figs. 4, 5, 6, and 7 are views in detail of the locking mechanism of the gates. Figs. 8, 9, and 10 are views illustrating a modified means for operating the gate.

In the drawings, 1 indicates fence-posts of 60 ordinary construction, and 2 guide-strips suitably secured thereto. It is to be noted that only the frame of the fence and gates are illustrated, the details of the fence and gate construction being omitted, as they form no 65 part of the invention.

This invention pertains more particularly to double-gate construction, and in order to make the description of the invention clearer reference will be had to one of the gates only, 70 it being understood that the gates are similar, with the exception of the locking means, which will be described in detail.

Pivoted at one end to one of the posts 1 is a track 2^a, said track terminating 75 at its opposite end at a point approximately flush with the gate-opening. This track consists of two parallel strips suitably spaced apart and provided with the series of cross-strips 3, which forms a ladder-like construction. This arrangement is to produce a gripping means for the operating means of the gate to be later described. Although this is the preferred form, a rack of any construction may be substituted. Near the free end 80 of the track there is provided in one of the parallel strips an elongated slot 4. Movable secured within this slot 4 is an end of a bell-crank 5, the opposite end of the crank being pivotally attached to an end portion of a strip 90 6, resting within a trackway 7. This trackway is of a box-like structure and is provided at one end with an opening 8, through which the bell-crank or lever 5 passes. This trackway extends a suitable distance from the gate, 95 and at its outer end or near said end is pivoted the strip 6, as at 9. The arrangement of parts is such that when the gates are closed the strip is slightly above the trackway.

This strip is adapted to be engaged by the 100 wheels or support of a vehicle, through which medium the gate is operated.

The gate consists of the end strip 10, rear strip 11, bottom strip 12, and the top strip 13. Mounted on the rear strip 11 is a support 14 105 for the gate. This support may be a wheel, as indicated in dotted lines; but I prefer to employ a segment of a wheel. The periphery

of the segment is provided with a series of teeth 15, adapted to engage the cross-pieces 3 of the trackway 2. Normally this trackway is in a horizontal position, or possibly 5 slightly inclined downward, in which position the gate is closed. When the strip 6 is depressed, the trackway by means of the bell-crank is elevated and the segment rolls or travels backward, and thereby opens the gate. 10 To facilitate this movement, a weight 16 is provided on the segment in such a way as to cause the gate to open quickly and after the trackway has regained its normal position to close slowly. By this arrangement sufficient opportunity is given for the passage of 15 a vehicle through the gate-opening. Upon a vehicle leaving the strip 6 the gate will ordinarily return to its closed position by its own weight or gravity; but to make the return positive the strip 6 extends a slight distance beyond its pivotal point 9. Through this means the weight of the vehicle will give an opposite movement to the bell-crank 5 just before it leaves the strip. 20 The top strip 13 of the gate extends beyond one side thereof and is provided with a series of depending straps 17, adapted to embrace the guide-strip 2. These straps hold the gate in operative position and also prevent 25 any lateral movement thereof. On the free portion of the top strip 13 is mounted a slideable weight 18, through which medium the weight of the gate can be adjusted on the fulcrum-point 19 of the operating segment or 30 wheel 14. This adjusting of the gate greatly assists the operation of the gate. 35 The track-approach 7 is provided on each side of the gate, together with similar connections between it and the trackway 2, in order 40 that the gate may be operated by a vehicle coming in either direction. 45 It is the intention of this invention that the gates shall only be operated or opened when pressure is on both of the tracks of the approach; otherwise the weight of live stock and the like may be given to one of the tracks, which in itself would be sufficient to elevate the trackway 2 and open the gates. To prevent this, an opening 20 is formed in the end 50 piece 10 of one of the gates and an arrow-shaped lever 20 is pivoted in the end or abutting piece of the opposite gate. This arrow is adapted to pass through the opening 20 when the gates are in a closed position, as 55 illustrated in Fig. 7. If sufficient weight is placed on the left-hand strip 6 to raise the track 2, the lower edge of the opening 20 will engage the lower part of the arrow 21 and the gate will be locked against movement. If 60 sufficient pressure is made on the opposite side, the arrow 21 will engage the upper edge of the opening 20; but if sufficient pressure is exercised on both simultaneously the gates will be raised and the arrow 21 will be free to 65 pass through the opening 20, allowing the

gates to open. These features are illustrated in detail in Figs. 4, 5, 6, and 7.

In Figs. 8, 9, and 10 is illustrated a modified means for operating the gate or elevating the tracks. In these figures the gate or gates *a* and 70 the trackway *b*, together with their parts, are constructed the same as in the preceding figures. Extending across the gateway and in alinement therewith is a housing *c*, the upper surface of which is flush with the surface of the 75 roadway. Within the housing is a cross-bar *d*, having on each end an upright bar *e*, which passes through suitable openings or apertures *f* in the upper surface of the housing *c*. The upper ends of the bars *e* are suitably secured 80 to the ends of the trackways *b* and are adapted to elevate the same. A wagon-way *g* or boxing is made to approach the gate from either side, and within this boxing are pivoted near one end the levers *h*, which have one 85 end suitably attached to the cross lever or bar *d*. A pivoted top or cover *j* is provided for the boxings and is so arranged that the weight thereon of a vehicle will force the same against the free end of the lever *h*, and by means of 90 the lever *d* and the uprights *e* the trackways *b* are elevated to operate the gate. This form of invention is much simpler than that described before; but in practice it is found to be efficient, economical, and advantageous. 95

From the foregoing descriptions it is thought that the construction and operation of the invention will be fully understood, it being noted that all changes may be resorted to that fairly fall within the scope of the 100 claims attached hereto.

Having thus fully described my invention, what I claim as new, and desire to secure by Letters Patent, is—

1. In a device of the character described, a 105 pivoted trackway, a gate, a circular support mounted on the gate and riding in the trackway, means carried by the gate for adjusting its weight on the support, and means for elevating the trackway.

2. In a device of the character described, a pivoted trackway, a gate, a support mounted on the gate and adapted to ride on the trackway, a guide for gate, depending straps on the gate embracing the guide, and means for 115 elevating the trackway.

3. In a device of the character described, a pivoted trackway, a gate, a strip on the gate extending beyond a side thereof, a support for the gate engaging the trackway, a guide 120 for the gate, straps depending from the strip and engaging the guide, an adjustable weight on the strip, and means for elevating the trackway.

4. In a device of the character described, a 125 pivoted trackway, a gate, a support for the gate engaging the trackway, a weight on said support, a guide for the gate, and straps carried by the gate and engaging said guide, and means for elevating the trackway.

5. In a device of the character described, a sliding gate, a strip on the gate extending beyond a side thereof, a guide for the gate, and straps depending from the strips and engaging the guide.

6. In combination, a pivoted track, a gate slidable thereon when the track is elevated, a vehicle-track comprising a boxing, a lever pivoted within the boxing, a connection between the lever and trackway, a cover bearing on the lever, and means for holding the gate against movement unless the track is elevated.

7. In combination, a pivoted track, a gate

slidable thereon when the trackway is elevated, a vehicle-track, comprising a boxing, a lever pivoted within the boxing a connection between the lever and trackway, and a cover for the boxing bearing on the lever.

In testimony whereof I affix my signature, in the presence of two witnesses, this 27th day ¹⁵ of January, 1905. ²⁰

GEORGE S. BUCK.
